United States Patent Office.

CYRUS W. SALADEE, OF NEWARK, OHIO.

Letters Patent No. 70,025, dated October 22, 1867.

IMPROVEMENT IN PROTECTORS FOR THE EDGES OF COLLARS.

The Schedule referred to in these Letters Patent and making part of the same.

TO ALL WHOM IT MAY CONCERN:

Be it known that I, CYRUS W. SALADEE, of Newark, county of Licking, State of Ohio, have invented a new and improved Mode of Constructing Paper Collars and Cuffs; and I do hereby declare that the following is a full and exact description thereof, reference being had to the accompanying drawings, and to the letters of reference marked thereon.

The nature of my invention consists in the peculiar arrangements hereinafter shown and described, of protecting the top edge of paper collars, and at the same time of imparting to the collar a style and variety of ornamentation at once novel and beautiful.

The manifest defect in all paper collars, notwithstanding the degree of perfection attained in their present manufacture, consists in the premature defacement of the top edge by contact with the neck of the wearer. The top edge of the collar, from perspiration and other causes, is soiled and defaced in one wearing to such a degree as to forbid its use a second time, and, indeed, in many cases, and I may say as a rule, the paper collars now in general use do not remain clean and tidy on the top edge even during the short period of one day's wearing. In fact, the collar is, during the warm days of summer, defaced in a few hours' time to such a degree as to require a change several times during a single day. I propose protecting, in any of the various ways hereinafter shown and described, the top edge of the collar, so that it will wear from two to three times as long as it now does without this protection, and at the same time add a degree of ornamentation in the finish of collars never before attained. In the drawings—

Figure 1 represents the "turn-down" or "Byron" collar, full shape and size, before it has been broken on the dotted line *c*, and turned down, with the shield-piece or figure B extending from one end of the collar to the other.

Figure 2 represents the same collar as shown in fig. 1 turned down and finished, showing the shield B as it appears when the collar is in use.

Figure 3 represents the inside surface of a standing collar, the dotted line D being the top edge of the same, with the shield-piece attached; and

Figure 4 represents the outside of the same when in use, showing the shield-piece turned down over the top edge of the collar.

The manufacture of paper collars with my improvement attached is substantially as follows:

For the turn-down collars I proceed in the usual way; but before breaking the collar to turn over, on the dotted line *c*, I apply the shield-piece or figure B, by first cutting out, with appropriate dies, the figure B, of such design as the fancy may suggest, from thin, strong paper of any color desirable, and paste or otherwise secure the figure upon the face of the collar A, as shown in fig. 3, before the collar is broken on the dotted line *c* and turned down. And the paper or other suitable material used for the shield or figure B, and pasted or otherwise attached to the face of the collar, should be manufactured expressly for the purpose, and which also should be perspiration-proof.

The application of this shield-piece B for the purpose of protecting the edge of the collar, I contemplate making in a variety of ways; and do not, therefore, limit my claim to the precise manner here shown; nor do I limit my claim to the kind of material that shall or may be used for this purpose, as any description of paper or other texture that is wholly or in part perspiration-proof will answer the purpose.

For standing collars the shield-piece B is cut out as already described, and pasted on the inside of the collar so as to let the scalloped edge E extend above the top edge of the collar, (dotted line D representing the top edge of the collar A, fig. 3,) and afterwards turned down over the edge of the collar, so as to expose the edge of the shield on the outside of the collar, as shown by fig. 4. I will here state that another method of using this shield-piece B, in connection with paper collars, is to manufacture them separate and independent of the collars; so formed that the shield is first buttoned on the neck-band of the shirt, and then button on the common white collar, and turn the top edge of the shield-piece down over the top edge of the collar. Thus there might be but one shield, B, accompany each box of collars, for in this case the shield is intended to be made of such material as will last the wearing of from eight to twelve collars.

As I have already stated, the variety of styles that this invention is susceptible of is almost unlimited.

For the fancy style of collars, such as we now have printed in fancy colors and figures, nothing can so much add to the finished appearance of the collar as the application of this shield-piece or figure B in any of the forms contemplated. And I will here state that I contemplate using the improvement herein described on linen collars, as well as on paper ones, and for which purpose it is equally well adapted; so also for linen or paper cuffs. For linen collars or cuffs the figure B may be applied thereto, same as specified for the paper collars, but a particularly fine appearance will be imparted to the collar by cutting the figure out of some kind of colored fabric, and then stitching upon the collar; so likewise for the cuffs, have the figure pasted or stitched upon the edge coming in contact with the wrist and hand, and thus afford the same protection to the edge of cuffs as to collars.

Having thus fully described the object and nature of my invention, what I claim as new, and desire to secure by Letters Patent, is—

I claim protecting the wearing edge of collars and cuffs by securing thereto the shield-piece B, in the manner and for the purpose substantially as shown and described.

CYRUS W. SALADEE.
